UNITED STATES PATENT OFFICE.

EDWIN B. STIMPSON, OF BROOKLYN, NEW YORK.

GAITER-BOOT.

SPECIFICATION forming part of Letters Patent No. 268,568, dated December 5, 1882.

Application filed October 10, 1882. (No model.)

To all whom it may concern:

Be it known that I, EDWIN B. STIMPSON, of the city of Brooklyn, in the county of Kings and State of New York, have invented a new and useful Improvement in Gaiter Boots and Shoes, of which the following is a specification.

My invention, which is applicable to boots and shoes for men, women, and children, relates to boots and shoes in which the upper part that surrounds the ankle is composed of elastic web. It has been common in boots or shoes of this kind to stitch on a strip of leather where the edge of the button-fly would come in a button boot or shoe, to stitch imitation button-holes in the elastic web, and to secure thereto imitation buttons.

The invention consists in a boot or shoe having the upper quarter on the inside of the ankle from the front to the back seam, and the outside quarter from the back seam to or near the front seam, both of elastic material, and having a button-fly attached to the inside ankle-quarter at the front seam and adapted to lap over the outside quarter, as fully herein-after described.

In the accompanying drawings, Figure 1 represents a perspective view of a boot embodying my invention. Fig. 2 represents the piece of elastic web which forms the upper quarter on the outside of the ankle, and also represents the button-fly. Fig. 3 represents the piece of elastic web which forms the upper quarter on the inside of the ankle, and Fig. 4 represents a sectional perspective view illustrating the way in which the pieces of web forming the outside and inside quarters of the boot or shoe are connected with the button-fly.

Similar letters of reference designate corresponding parts in all the figures.

A B designate respectively the two pieces of elastic web which form the upper quarters of the boot on the outside and inside of the ankle. These two pieces of web are connected by the back seam of the boot. For men's boots the uppers are foxed; but for women's and children's boots and shoes they may or may not be foxed.

C designates a button-fly, which may be made of elastic web, or of cloth, leather, or other material, and C' designates the button-fly lining.

The piece of web B, which forms the inside of the boot, extends from the back seam or 55 the back of the boot to the front seam, a, and by the front seam the said piece B is connected with the button-fly C and fly-lining C', and with the usual front stay, a', when a front stay is applied to the seam. The piece of web 60 A on the outside of the boot may extend from the back seam clear to the front seam, a; but as this would tend to make the boot clumsy I preferably continue the piece A near to said front seam only and but a little way under the 65 button-fly, and between it and the button-fly lining C', as best shown in Fig. 4. The piece A is secured to the edge or marginal portion of the fly C by one or more rows of stitching, b, and the stitching may extend through the 70 fly, as shown, thereby securing it down; or the edge of the fly may be left free, like an ordinary fly. In the fly C are formed real button-holes c, and d designates buttons the eyes of which are inserted through the button-holes and sewed to the piece A and to the fly-lining C'. If the piece of web A does not extend under the fly C as far as the buttons d, the latter may be sewed to the fly-lining C' only, and they cannot tear off, as there is no strain 80 upon them.

My improved boot and shoe presents the precise appearance of a button boot or shoe, and cannot be readily distinguished therefrom, while the button-fly always fits closely and 85 neatly on the upper, and there will be no creases on the instep, and, moreover, no buttoning or unbuttoning is necessary, buttons are not liable to come off in wear, and button-holes will not wear out.

What I claim as my invention, and desire to 90 secure by Letters Patent, is—

A boot or shoe having the upper quarter on the inside of the ankle from the front to the back seam, and the outside quarter from the 95 back seam to or near the front seam, both of elastic material, and having a button-fly attached to the inside ankle-quarter at the front seam and adapted to lap over the outside quarter, substantially as and for the purpose 100 herein described.

EDWIN B. STIMPSON.
